AUTOMOBILE TAIL LAMP

Harold W. Pilkey, Detroit, and Charles F. Gitschlag, St. Clair Shores, Mich., assignors to Chrysler Corporation, Highland Park, Mich., a corporation of Delaware

Application July 29, 1957, Serial No. 47,116

Term of patent 7 years

(Cl. D48—32)

FIG. 1

FIG. 3

Fig. 1 is a side elevational view of an automobile tail lamp showing our new design;

Fig. 2 is a front elevational view thereof;

Fig. 3 is a top plan view thereof;

Fig. 4 is a sectional view taken on the line 4—4 of Fig. 2; and

Fig. 5 is a sectional fragmentary view taken on the line 5—5 of Fig. 1.

We claim:

The ornamental design for an automobile tail lamp, substantially as shown.
